UNITED STATES PATENT OFFICE.

JOSEPH ARDO, OF NEWHALL, WEST VIRGINIA.

SAFETY-BOAT.

1,364,911.

Specification of Letters Patent. Patented Jan. 11, 1921.

Application filed July 1, 1920. Serial No. 393,349.

To all whom it may concern:

Be it known that I, JOSEPH ARDO, citizen of the United States, residing at Newhall, in the county of McDowell and State of 5 West Virginia, have invented certain new and useful Improvements in Safety-Boats, of which the following is a specification.

This invention relates to life-boats for ships and it has for an object to provide a 10 novel form of life-boat characterized by great stability.

More specifically the invention has for an object to provide such a boat with the compartment for the occupants mounted to prevent 15 rolling movement.

Another object relates to the provision of a novel form of steering mechanism.

For further comprehension of the invention, and of the objects and advantages 20 thereof, reference will be had to the following description and accompanying drawings, and to the appended claim in which the various novel features of the invention are more particularly set forth.

25 Figure 1 of the drawings is a plan view of a ship's life-boat constructed according to the invention.

Fig. 2 is a central longitudinal vertical section thereof.

30 Fig. 3 is a horizontal section on the line 3—3 of Figs. 2 and 4.

Fig. 4 is a transverse section on the line 4—4 of Fig. 3.

As here shown my improved boat comprises 35 an outer hull of circular cross section and divided into a lower member 1 and an upper member 2 which are joined together in any suitable manner, the member 1 having the usual fore and aft stream line construction, this member being 40 hereinafter referred to as the hull and the member 2 as the cover, this latter being provided with suitable doors 3 and portholes 4.

Within the hull 1 is pivotally suspended 45 an inner hull 5 which is adapted to contain the occupants of the boat, this hull being pivoted on an axis extending along the median line of the boat, and being provided at opposite ends and near the top thereof with 50 socket projections 6 which take over studs 7 on the hull 1, antifriction bearings 8 being preferably provided between the sockets and studs.

In order to enable the boat to be steered 55 from within the inner hull 5 the rear stud

7 is made hollow and the tiller ropes 9 are led forwardly from the usual rudder 10 through this hollow stud and into the inner hull 5 which is provided with a suitable registering perforation. These tiller ropes 60 9 are connected at their forward end to opposite sides of a disk 11 pivoted on a bracket 12 on the stern of the inner hull 5. This disk 11 has rigidly fixed thereto a bevel gear 13 which is engaged by a second bevel gear 14 on a pintle 15 projecting forwardly from the bracket 12, the steering wheel 16 being rigid with the bevel gear 14. As shown most clearly in Fig. 2, the face of the disk 11 is substantially in the axial line of 70 the stud 7 so that the relative swinging movement of the outer and inner hulls will not have any disturbing influence on the rudder, which, as will be apparent, can be readily operated from within the inner hull. 75

To maintain the stability of the boat the outer hull 1 has fixed to the underside thereof a keel which preferably consists of a tube 18 having a weight 19 extending along the underside thereof, while to maintain 80 fore and aft stability and keep the bow of the boat from dipping too deeply into the waves a pair of tapering tubes 20 are secured on the sides of the hull adjacent the bow these tubes inclining downwardly and 85 outwardly from the bow rearwardly and decreasing in width from front to rear ends.

The boat may be propelled by a series of propellers of which one pair, 22 are mounted on longitudinally extending stub shafts 90 23, and the other pair 24, on transverse shafts 25. The shafts 23 and 25 have bevel gears 26 and 27 respectively on their inner ends, the gears 26 meshing direct with bevel gears 28 on opposite ends of a drive shaft 95 29, the gears 27 and 28 engaging through the medium of idlers 30, standards 31 being provided for supporting these gears. The shaft 29 may be driven by a suitable motor not shown. 100

My improved life-boat may be carried in the usual manner on the deck of a ship and may be lowered by the usual means. When in the water the occupants will be completely sheltered from waves or flying spray 105 while the construction reduces to a minimum rolling movement of the compartment containing the occupants.

Having thus described my invention what I claim as new and desire to protect by Let- 110

ters Patent of the United States is as follows:—

A life-boat comprising an outer hull, an inner hull pivotally suspended in said outer hull, the rear suspension member for the inner hull having an axial opening there-through, a rudder, a disk pivotally mounted at the stern of the inner hull, tiller ropes

leading from said rudder to said disk, a bevel gear fixed co-axially to said disk, a second bevel gear meshing with the first bevel gear, and a steering wheel fixed co-axially to said second bevel gear.

In testimony whereof I have affixed my signature this 24th day of June, 1920.

JOSEPH ARDO.
